CLAIM

The ornamental design for an archway partition panel as shown and described.

DESCRIPTION

FIG. 1 is an upper perspective view of the archway partition panel showing my design.

FIG. 2 is a front elevation view thereof;

FIG. 3 is a back elevation view thereof;

FIG. 4 is a side elevation view thereof;

FIG. 5 is an opposite side elevation view thereof;

FIG. 6 is an enlarged perspective view thereof, taken from portion "6" in FIG. 5;

FIG. 7 is a top plan view thereof;

FIG. 8 is a bottom plan view thereof;

FIG. 9 is a top perspective view thereof, showing the archway partition panel in a state of use; and,

FIG. 10 is an enlarged perspective view thereof, taken from portion "10" in FIG. 9.

The dash-dash broken lines in the drawings represent portions of the archway partition panel and form no part of the claimed design. The other broken lines in FIG. 9 represent environmental subject matter only and form no part of the claimed design. The dash-dot-dash broken lines shown in FIGS. 1 through 10 indicate that any portion of the archway partition panel beyond what is shown forms no part of the claimed design.

The dash-dot-dot broken lines of FIGS. 5, 6, 9, and 10 are included to show a partially enlarged view only and form no part of the claimed design.
